UNITED STATES PATENT OFFICE.

JAMES MALLON, OF NEW ORLEANS, LOUISIANA.

HORSE-POWER.

No. 841,412.

Specification of Letters Patent.

Patented Jan. 15, 1907.

Application filed February 16, 1906. Serial No. 301,495.

To all whom it may concern:

Be it known that I, JAMES MALLON, a citizen of the United States, residing at New Orleans, in the parish of Orleans and State of Louisiana, have invented certain new and useful Improvements in Horse-Powers; and I do hereby declare the following to be a full, clear, and exact description of the invention, such as will enable others skilled in the art to which it appertains to make and use the same.

This invention relates to improvements in horse-powers, and has for its primary object to provide a drum and sweep mounted to revolve independently of each other, with means for interlocking said drum and sweep and means for braking said drum, with operating-levers for said means carried by said sweep and extending to positions adjacent the seat for the operative carried by the sweep.

While the invention is not limited to the specific construction disclosed, for the purpose of more clearly understanding the invention reference is had to the accompanying drawings, illustrating a practical embodiment of same, the novel features of which will be more succinctly pointed out in the claims.

In the drawings, Figure 1 is a view in side elevation, a portion of the sweep being broken away. Fig. 2 is a plan view, portions of the sweep and drum being broken away; and Fig. 3 is a vertical section through the lower bearing and hollow shaft.

1 is a framework provided, as is customary, with runners for dragging the horse-power to different positions, 2 designating upright standards for supporting the guiding-roller 3 for the cable 4.

5 is a vertical hollow shaft rigidly secured, as by the clamping means 6, to the cross-beams 1^a of the frame. 7 is the winding-drum, revolvably mounted on said hollow shaft 5. At the lower end of the drum there is preferably provided an annular flange 8 for preventing the cable from slipping down when slack. The upper end of the drum is provided with the peripherally-notched top flange member 9, which in the drawings is illustrated as forming the top plate of the drum, projecting beyond the periphery of the drum and provided with the notches or recesses 9^a for a purpose hereinafter referred to. 10 designates the sweep, provided with a seat 10^a on its short arm. This sweep is rev-

olvably mounted on the upper end of the hollow shaft 5 by means of the journal-bearing having the upper and lower plates 11 11^a, the lower plate 11^a adapted to rest on a spacing-collar 12, interposed between the sweep and the drum.

13 is a sliding bolt carried by the lever 14, pivotally supported, as at 15, by the sweep. This sliding bolt is mounted adjacent to and co-operates with the notches 9^a and forms a portion of the means for interlocking the drum to the sweep.

16 is an angle-plate carried by the sweep for guiding and limiting the movement of the sliding bolt, and 16^a is an angle-plate to limit the upward movement of the sweep.

17 designates a braking-band encircling the drum below the flange 8, one end of the band being secured, as by the angle-plate 18, to one of the cross-beams 1^a. The other end of the braking-band is connected, as by the tightening-bolt 19, with the end of an operating cable or chain 20, reeving over a pulley 21, supported by the bearing 22, thence passing downwardly and reeving below a suitably-supported pulley 23, thence passing laterally of the frame, (as at 20^a, Fig. 2,) thence passing below a suitably-journalled pulley 24, (shown in dotted lines, Fig. 2,) said pulley 24 mounted adjacent the lower end of the hollow shaft 5, and finally passing upwardly through said hollow shaft (as at 20^b, Fig. 1) and connected, preferably by a swivel, to the short arm of an operating-lever 25, suitably supported, as by the bearing 26, on the plate 11. It will be seen that this lever 25, as well as the lever 14, extends adjacent the seat for the operative.

It will be understood that the lateral ear 17 on the braking-band is bored to loosely receive the bolt 19, which is adjusted by means of the nuts 19^a, thus forming means for taking up the slack of the brake.

From the foregoing description the operation is obvious, it being seen that the operating-levers are in easy control of the operative, so that the drum may be readily interlocked to the sweep or released therefrom and when released the drum being under control of the braking mechanism.

Having thus described the invention, what I claim is—

1. In a horse-power, the combination with a vertical hollow shaft, of a drum and sweep carried by said shaft and independently revolute relatively to each other, means for in-

terlocking and releasing said sweep and drum, a brake at the lower end of said drum, an operating-handle for said brake supported by said sweep, flexible means passing through 5 said hollow shaft and connecting said handle with said brake, and means carried by said sweep for operating said interlocking means, substantially as described.

2. In a horse-power, the combination with 10 a hollow vertical shaft, of a drum and a sweep mounted to revolve independently thereon, a peripherally-notched member carried by said drum, a locking-bolt carried by said sweep adjacent said peripherally-notched 15 member and means for operating said bolt into and out of engagement therewith, a brake-band encircling the lower end of said

drum, secured at one end to a rigid support, a system of pulleys disposed between the free end of said brake end and the lower end of 20 said hollow shaft, an operating-lever carried by said sweep adjacent the upper end of said hollow shaft, and flexible means secured at one end to said operating-lever, thence passing around said system of pulleys and at its 25 other end connected to the free end of said brake-band, substantially as described.

In testimony whereof I affix my signature in presence of two witnesses.

JAMES MALLON.
